UNITED STATES PATENT OFFICE

2,581,938

APPARATUS FOR APPLYING POWDER
TO THREAD

Carl R. Swanson, Central Village, and Ernest W. Olson, Swansea, Mass., and Frank L. Armitage, Barrington, R. I., assignors to The Firestone Tire & Rubber Company, Akron, Ohio, a corporation of Ohio

Original application August 4, 1947, Serial No. 765,998. Divided and this application March 5, 1949, Serial No. 79,808

2 Claims. (Cl. 91—46)

1

This invention relates to an improved method of manufacturing latex thread. An important object of the invention resides in the provision of an improved method for the manufacture of extruded latex thread.

This application is a division of parent application Serial No. 765,998, filed August 4, 1947, now abandoned.

Another object of the invention is to provide an improved method and apparatus for applying a powder to thread after the fixing and drying operations have been completed.

Other objects and advantages will become apparent to persons skilled in the art upon examination of the drawings, the specification and the claims appended thereto.

In the drawings:

Fig. 1 is an elevational view, partly in section, illustrating extrusion and fixing stages of the method;

Fig. 2 is an elevational view illustrating the final wash, drying, powdering and windup stages of the method; and

Fig. 3 is a view in perspective showing the details of the apparatus employed to effect an improved method of powdering latex thread.

Referring to Fig. 1, a container 10 is provided for the reception of latex compound in liquid form, said compound being fed from one or more closed tanks 11 and 12, container 10 being upwardly open to the atmosphere. Suitable conduits 15 and 16, leading from tanks 11 and 12, respectively, lead to a single connecting conduit 19, the lower end of which extends into container 10. A pair of control valves 22 and 23 are provided in conduits 15 and 16 respectively. A level controlling conduit 23 provides communication between tanks 11 and 12, leading from the upper walls thereof, and a point 26 within container 10, to provide an automatic fluid level control within that container. It is apparent that as liquid latex 30 rises within container 10 sufficiently to block the lower end of conduit 23 from the atmosphere, fluid flow through conduits 15, 16 and 19 will be terminated due to the establishment of a partial vacuum in tanks 11 and 12.

During operation of the device, a steady stream of the liquid compound 30 flows through conduit 32, leading from a lower wall portion of container 10 to terminate in nozzle 33, producing a metered flow of latex compound as it extrudes from nozzle 33. Thread 35, which results from said extrusion, is drawn by suitable power actuated pulleys 37 through a fixing bath 38

5 maintained within a suitable shallow container 39. Fixing or coagulating bath 38 may be an acid bath of a type well-known in the art, the composition of which forms no part of the present invention. From the coagulating bath the thread 35 is drawn over roller 37 to enter a wash bath, for example, through a bath of clear water 41, partially filling shallow container 43. From the first wash bath, thread 35 may be drawn 10 over roller 45 to enter a second wash bath of clear water 47, within container 48.

The coagulated and doubly washed uncured latex thread 35 is drawn from the second wash bath by pulley 50 to enter a suitable drying chamber generically designated 52, of any well-known type such as a steam, hot air, or electric dryer. The temperature within oven 52, and the rate of movement of thread 35 therethrough are so coordinated as to effect only a partial cure 20 of the thread during passage through the dryer. The circumferential speed of pulley 55 is maintained equal to the circumferential speed of pulley 50 and consequently no substantial stretching of thread 35 takes place during passage 25 thereof through dryer 52. As thread 35 leaves pulley 55, it is drawn upwardly as shown by pulley 57, the circumferential speed of which is greater than that of pulley 55. Since both pulleys 55 and 57 present a substantial degree of friction, slipping of thread 35 in the pulley groove surfaces does not occur and consequently a stretching of the thread is effected, the degree of stretch being proportional to and controllable by the circumferential speed differential existing between pulleys 55 and 57 respectively.

From pulley 57, thread 35 is drawn by pulley 60 across and adjacent to the planiform horizontally disposed upper surface of the powdering unit, generically designated 65. A suitable dusting powder, such as talc 66, is applied by unit 65, in a manner hereinafter described, the partially cured and powder-dusted thread, as a finished product, being drawn from pulley 60 by pulley 67, to be wound on a driven spool 69.

Referring to Fig. 3, powdering unit 65 may comprise a vertical member 71 upon which a divergent element 72 finds its support, a horizontally disposed flat element 73 being affixed to element 72. A pair of flat elements 75 and 76 are slidably mounted in respect to element 72 and supported thereby, elements 75 and 76 being in a common horizontal plane with element 73 and sufficiently spaced from the margin thereof to permit relative transverse movement of elements 75 and 76 in respect to element 73.

A pair of brackets 80 and 81 depend respectively from elements 75 and 76, to provide pivotal connection for a pair of radius rods 83 and 84, said rods being in turn pivotally connected to a pair of drive wheels 87 and 88 mounted for rotation with drive shaft 89. Rods 83 and 84 are connected to wheels 87 and 88 at points radially removed from the wheel centers to provide reciprocatory motion of rods 83 and 84 upon rotation of shaft 89. Shaft 89 is provided with a 10 suitable keyed sprocket 92 driven by chain 93 from a suitable source of power, not shown, for the reciprocation of elements 75 and 76, simultaneously in opposite directions.

Supported to extend upright from elements 15 75 and 76, are a pair of notched guide elements 96 and 97. Said guide elements allow free axial movement of thread 35 while causing lateral displacement equal to the reciprocatory movement of said elements. A suitable quantity of 20 dusting powder, such as talc, is spread over elements 73, 75 and 76, and as thread 35 moves across the top of dusting unit 65, the thread is not only drawn through the dust thereon, but the lateral displacement of the thread in opposite directions by guides 96 and 97, causes a rolling action of the thread, as shown by arrows 100 and 101, especially in that portion extending across element 73, to insure complete dusting of the entire thread surface.

Modification may of course be resorted to without departure from the spirit and scope of the invention, as defined in the following claims.

What is claimed is:

1. In a device for applying powder to the outer surface of thread, in combination with a supported member having a flat, upper surface, a pair of members having flat, upper surfaces co-planar with said surface of said supported member, and positioned laterally adjacent and on 40

opposite sides of said supported member, said pair of members being mounted for slidable displacement transversely of said supported member in the common plane of said members, guide means for the thread on each of said pair of members, and means connected to said pair of members and arranged to reciprocate them in opposite directions.

2. In a device of the character described, a table-like assembly comprising a flat table top divided into a fixed, central portion and flat, side portions having upper surfaces co-planar with the upper surface of said central portion and movable with respect to said central portion in the common plane of said surfaces, guide means for a moving thread on said side portions, and means for continuously reciprocating said side portions in opposite directions, comprising a driven shaft, and radius arms eccentrically associated with said driven shaft and operatively connected to said side portions, said table portions adapted to hold a quantity of dusting powder, and said guide means adapted to roll a thread about its axis as it passes over said table assembly.
